UNITED STATES PATENT OFFICE.

FRANK S. BARKS, OF ST. LOUIS, MISSOURI, ASSIGNOR TO LINCOLN STEEL AND FORGE COMPANY, OF ST. LOUIS, MISSOURI, A CORPORATION OF MISSOURI.

MINE CAR.

Application filed April 17, 1922. Serial No. 553,950.

To all whom it may concern:

Be it known that I, FRANK S. BARKS, a citizen of the United States, residing at city of St. Louis, State of Missouri, have 5 invented a certain new and useful Improvement in Mine Cars, of which the following is a full, clear, and exact description, such as will enable others skilled in the art to which it appertains to make and use the 10 same, reference being had to the accompanying drawings, forming part of this application, in which—

Figure 1 is an end elevational view partly in section of my improved mine car truck. 15 Figure 2 is a vertical cross sectional view on the line 2—2 of Figure 1.

Figure 3 is a side elevational view partly in vertical section of a modified form of spring housing and support. 20 Figure 4 is a plan view of the spring housing shown in Figure 3.

This invention relates to a new and useful improvement in mine cars of that type shown in United States Letters Patent No. 25 1,389,928 granted to me September 6, 1921. The object of my present invention is to provide simple and cheap means for yieldingly supporting the car frame, or truck frame, as it is sometimes called, on the axle, where- 30 by there is permitted a limited vertical movement of the axle or frame with relation to each other, the frame being yield- ingly supported upon the axles.

In the drawings, 1 indicates the side strap, 35 which preferably extends from end to end of the car and which strap is provided with depressions or bent portions 2 near each end forming semi-cylindrical recesses for receiving the journal boxes 3.

40 4 indicates the axle passing through the journal boxes and having a wheel 5 on each end. The construction of the journal box and method of mounting the wheels thereon form no part of my present invention.

45 6 indicates the flanged member preferably in the form of a channel whose ends are riveted to the bent portions of the strap 1 and form closures for the semi-cylindrical recesses or box openings in said strap pro- 50 duced by the bent portions 2 thereof. These channels extend transversely the frame above and substantially parallel to the axles 4. The web of each channel is provided with

a circular opening above each journal box and in this opening is loosely arranged a 55 thimble 7 having outwardly extending flanges 8 at its lower end which are de- signed to engage the under surfaces of the web of the channel. Thimble 7 constitutes a spring housing and spring seat for a frame 60 supporting spring 9. The lower end of this spring rests upon the upper surface of the journal box 3.

10 indicates timbers constituting the floor of the car, which timbers rest upon straps 1 65 and the channels 6, the upper surfaces of which are preferably flush to accommodate the timbers in the particular form of mine car shown.

To remove the axle, it is only necessary to 70 take out the cotter pins 11 when the wheels may be taken off and the axle moved longitudinally through its boxes. To remove the boxes, they can be driven longitudinally through the housing 2 and past spring 9. 75 When the box is removed, the spring and its housing thimble may be readily removed.

In assembling the parts, the reverse op- 80 eration is resorted to: First, the thimble is placed in position, after which the spring is inserted in place and held up while the journal box is being introduced, after which the axle is arranged in position and the wheels applied, said wheels being finally held in position by the cotter pin. 85

In Figures 3 and 4, I have shown a modified form of spring housing in which the thimble 12 is provided with perforated lugs 13 by which said thimble is secured in position to the framing or flooring of the car 90 as the case may be. In this form, there is a plunger 15 having a shoulder 16 for co- operating with the spring 17 arranged within the housing. The lower end of the plunger passes through an opening, say in the web 95 of the cross channel and rests upon the upper surface of the journal box. In this form of construction, the spring housing may be removed without dismantling the axle, wheels and boxes, or if such parts are 100 dismantled, the housing spring and plunger will remain in operative position. In this form of my invention, when assembling the parts, if it is desired to place the springs under slight initial compression, this can 105 readily be done by making the spring of

proper length and strength and then turning down the nuts on the upper end of the fastening devices 14.

Having thus described my invention, what

5 I claim is:

1. In a mine car, an axle, a car frame member comprising a channel iron extending lengthwise of the car axle and above the same with its web horizontal and provided 10 with apertures near its ends, spring receiving thimbles inverted and extending upwardly through said apertures and flanged at their open lower ends to engage said channel webs, and spring seated in said thimbles 15 and supporting the latter from the axle.
2. In a mine car, spaced axles, channel iron frame members extending across the car longitudinally of and above said axles, a flat bar extending longitudinally of the car 20 crossing said channels near the ends of the latter, there bent downwardly and upwardly to form a journal box container and secured to said channels at the sides of the container forming portions.
- 25 3. In a mine car, spaced axles, channel

iron frame members extending across the car longitudinally of and above said axles with their webs horizontal and provided with an aperture near each end, inverted thimbles extending upwardly through said apertures, a flat bar extending longitudinally of the car and crossing said channels near the ends of the latter, there bent downwardly and upwardly to form journal box containers and secured to the vertical flanges of said channels at the sides of the container forming portions, journal boxes in said containers, and springs compressed between said journal boxes and the bases of the thimbles.

4. In a mine car, spaced axles, journal boxes on said axles, flat bars extending lengthwise of the car at the sides of the latter and bent semi-cylindrically about each of said journal boxes, channel irons extending longitudinally of said axles with their flanges turned downwardly and secured to the bent portions of said bars.

In testimony whereof I hereunto affix my signature this 10th day of April, 1922.

FRANK S. BARKS.
